CLAIM

The ornamental design for a solar battery affixing frame, as shown and described.

DESCRIPTION

FIG. 1 is a right side elevational view of a solar battery affixing frame showing our new design, the left side elevational view being a mirror image thereof;
FIG. 2 is a front elevational view thereof;
FIG. 3 is a rear elevational view thereof;
FIG. 4 is top plan view thereof; and,
FIG. 5 is a bottom plan view thereof.
